EARL W. MYERS, ALL OF SEWICKLEY, PENNSYLVANIA.

METALLIC TIE.

1,175,337.

Specification of Letters Patent. Patented Mar. 14, 1916.

Application filed October 28, 1915. Serial No. 58,330.

To all whom it may concern:

Be it known that I, CHARLES BUSS, a citizen of the United States, residing at Pittsburgh, in the county of Allegheny and State 5 of Pennsylvania, have invented certain new and useful Improvements in Metallic Ties, of which the following is a specification.

This invention relates to metallic ties and has for its object to provide, in a manner 10 as hereinafter set forth, a metallic tie having means for insulating the track rail from the tie body, said means further constituting a cushion for the track rail.

A further object of the invention is to 15 provide a track tie including a metallic body and a metallic chair plate with means interposed between the plate and body to set up a cushion for the plate and to further insulate the plate from the body.

20 A further object of the invention is to provide a metallic tie, in a manner as hereinafter set forth, having a filler of non-conducting material for reinforcing the tie body and further including with the tie 25 body a chair plate connected therewith through the medium of the filler.

Further objects of the invention are to 30 provide a metallic tie which is simple in its construction and arrangement, strong, durable, efficient and convenient in its use, readily set up and inexpensive.

With the foregoing and other objects in view the invention consists of the novel construction, combination and arrangement of 35 parts as hereinafter more specifically described and illustrated in the accompanying drawings, wherein is shown an embodiment of the invention, but it is to be understood that changes, variations and modifications 40 can be resorted to which come within the scope of the claims hereunto appended.

In the drawings wherein like reference characters denote corresponding parts throughout the several views: Figure 1 is a 45 perspective view of a metallic tie in accordance with this invention. Fig. 2 is a cross sectional view through one end of the tie. Fig. 3 is a side elevation of a modified form of tie body.

50 Referring to Figs. 1 and 2 of the drawings, 1 denotes a flat rectangular metallic member constituting a tie body and provided near each end and at each side with a pair of depending flanges 2, 3, the former

having its inner edge curving downwardly 55 and outwardly as at 4 and the latter having its inner edge curving downwardly and inwardly as at 5. The inner edges 4, 5, of the flanges 2, 3, are spaced from each other for the purpose to be presently referred to. 60

The flanges 2, 3, at each end of the tie body form a pocket 6 and arranged in each of said pockets 6 is a filler member 7 constructed of wood or other suitable non-conducting material. Each of the filler members 6 is fixedly secured in position by a pair of bolts 8, 9, which are provided with nuts 10. The bolts 8 extend through the flanges 2 and the filler member 7 and the bolts 9 extend through the flanges 3 and the 70 filler member 7. Each of the filler members 7 has a longitudinally extending centrally disposed slot 11 which registers with a slot 12, formed in the tie body 1.

Mounted upon each end of the tie body 75 is a chair plate 13 having each side formed with a depending arm 14, only one of which is shown, and each of the arms 14 extends down between the edges 4, 5, of a pair of flanges 2, 3, and the side edges of each arm 80 14 are spaced from said edges 4, 5, or in other words, out of contact therewith. The edges of each of the arms 14 are indicated at 15, 16 and each of said edges curves downwardly and inwardly. The arms 14 85 abut against the filler members 7 and are coupled thereto through the medium of transversely extending bolts 17, which extend through the arms 14 and filler members 7 and are provided with nuts, these 90 latter not being shown. Each of the chair plates 13 has a pair of spaced longitudinally extending slots 18, 19 alining with the slot 12 in the tie body 1.

Interposed between the chair plates 13 95 and the tie body are cushioning members 20 formed of non-conducting material and the function thereof is to insulate the chair plates 13 from the tie body 1, as well as provide a cushion for a track rail, not shown. 100 Each of the cushioning members 20 is formed with a slot 21 registering with the slot 12 of the tie body and with the slots 18, 19, of the chair plate. As the filler members 7 are constructed of non-conducting 105 material the arms 14 are insulated from the tie body.

In the modified form shown in Fig. 3

the tie body is indicated at 22 and is in the form of a channel iron, with the side flanges 23 thereof cut away at 24. The forward edges of the cut away portion 5 curve downwardly and forwardly as at 25 and the rear edges curve downwardly and inwardly as at 26. Openings 27 are provided in the flanges of the tie body for the passage of bolts to secure the filler member 10 and chair plates in position. The cut away portions 24 provide the sides of the tie body with a series of depending flanges, the outer flanges being shorter than the intermediate flanges. The openings or slots in the tie 15 body, cushioning members, and chair plates provide means for the positioning of track rail fasteners. It will be noted however, that any form of track rail fastener can be employed and if desired the slots can be dispensed with. The tie body may have a filling of concrete which can extend from 20 end to end thereof.

What I claim is:—

1. A metallic tie comprising a tie body 25 having a series of depending spaced flanges at each side thereof, a chair plate mounted upon the tie body at each end thereof and having each side provided with a depending arm extending between the pair of 30 spaced flanges, said flanges being spaced therefrom, an insulating member interposed between said chair plate and said tie body and means for connecting said arms to said tie body.
2. A metallic tie comprising a tie body 35 having a series of depending spaced flanges at each side thereof, a chair plate mounted upon the tie body at each end thereof and having each side provided with a depending 40 arm extending between the pair of spaced flanges, said flanges being spaced therefrom, an insulating member interposed

between said chair plate and said tie body, 45 filler members mounted against the lower face of said tie body at each end thereof, means for connecting said filler member to the tie body, and means for connecting said arms to said filler member.

3. A metallic tie comprising a tie body 50 having a series of depending spaced flanges at each side thereof, a chair plate mounted upon the tie body at each end thereof and having each side provided with a depending arm extending between a pair of spaced flanges, said flanges being spaced therefrom, an insulating member interposed between 55 said chair plates and said tie body, filler members mounted against the lower face of said tie body at each end thereof, means for connecting said filler members 60 to the tie body, and means for connecting said arms to said filler members, said filler members constructed of non-conducting material.

4. A metallic tie comprising a tie body, 65 having a series of depending spaced flanges at each side thereof, a chair plate mounted upon the tie body at each end thereof and having each side provided with a depending arm extending between a pair of spaced 70 flanges, said flanges being spaced therefrom, an insulating member interposed between said chair plate and said tie body and means for connecting said arms to said tie body, said tie body, chair plates, cushioning members and filler members slotted for 75 the passage of rail fasteners.

In testimony whereof I affix my signature in the presence of two witnesses.

CHARLES BUSS.
